BUCKLE

Bo Björkström, Varberg, Sweden

Application March 5, 1946, Serial No. 651,998
In Sweden August 23, 1945

5 Claims. (Cl. 24—201)

1

The present invention relates to buckles to be used for waist-belts, for holding the cover of bags and portfolios in closed position, as holder for pens, watches and other articles at pockets, as clips by cyclists, as shoe-buckles and so on. One object of the invention is the provision of a buckle the clasping and unclasping of which may be effected rapidly and with simple manipulations. A further object of the invention is the provision of a buckle with simple construction and which will be very cheap in manufacture. These and other objects of the invention will be made clear by the following description with reference to the accompanying drawings illustrating some embodiments of the invention.

In the drawings, Fig. 1 is a plan view of a blank for a buckle. Fig. 2 is a plan view of the buckle when finished. Fig. 3 is a section on the line III—III of Fig. 2. Fig. 4 is a side elevation of the same buckle in use for a strap and Fig. 5 is a plan view of the same arrangement. Fig. 6 is a plan view of the buckle according to a second embodiment and Fig. 7 is a section of the same buckle on the line VII—VII of Fig. 6 in connection with a belt. Fig. 8 is a plan view of a portion of a closure strap of a portfolio with a securing device for a buckle. Fig. 9 is a side elevation of the same strap with the securing device and Fig. 10 is a view of the same strap with the securing device from the rear side. Fig. 11 is a plan view of the buckle with the strap connected therewith and the same securing device in operative position. Fig. 12 is a section on a larger scale on the line XII—XII of Fig. 11. Figs. 13, 14 and 15 are rear, side and front elevations respectively of a buckle according to a third embodiment. Fig. 16 is a side elevation of this buckle used as holder of a pen indicated by dot-and-dash lines. Fig. 17 shows by dot-and-dash lines a side elevation of a pen with connecting means for the buckle of a design other than that shown in Fig. 16. Figs. 18, 19 and 20 are end elevation, plan view and side elevation, respectively, of a further embodiment of the buckle.

In the embodiment of Figs. 1—5, 1 indicates a plate or disc of substantially rectangular or oval shape. This plate is provided with a tongue 2 extending substantially in the longitudinal direction of the plate, the extreme end portion 3 of the tongue being bent out of the plane of the plate. Behind the tongue holes 5 are provided and behind these holes a shorter tongue 6 is formed at one of the short sides of the plate. The tongues 2, 6 extend from the plate 1 in opposite directions from the plane of the plate 1, but

their extreme end portions are bent to the same side in relation to this plane. The longitudinal edge portions 7 are bent about the lines 8 substantially at right angles to this plane. The tongue 2 projecting from an intermediate or substantially central portion of the plate is considerably longer than the other tongue 6 and in consequence the tongue 2 has a substantially greater resilience.

10 By means of rivets or the like, which are inserted through the holes 5, the buckle described is attached, for example, to the end portion of a leather belt or strap 9, which is attached to the rear side of the buckle, i. e. the side opposite the edge portions 7 and the extreme ends of the tongues 2, 6. When the belt 9 has been brought to embrace the object, about which it is to be clasped, the outer end of the tongue 2 is inserted through a hole 10 in the belt, which extends between the edges 7 of the buckle, whereupon the belt is stretched so that after some resilient bending of the tongue 2 the tongue 6 can engage with an adjacent hole 10 in the belt 9. The portion of the belt between the holes 10 engaging with the tongues is maintained in stretched condition by the resilient action particularly of the tongue 2, so that the belt can be disengaged only by pulling the belt in angular direction from the plane of the plate 1, whereby the one or the other or both of the tongues 2, 6 due to their resilient capacity will be bent out from the plane of the plate and disengaged from the holes 10. Both the clasping and unclasping of the buckle are effected by suitable movements of and pull in the belt, and consequently both of these operations can be effected rapidly and easily. It may be advantageous to provide the holes 10 of the belt with metal eyelets.

15 The embodiment shown by Figs. 6 and 7 is substantially of the same construction as that described above, but, as distinguished from the latter, it is provided with a stretching member for the belt. This stretching member is formed by an extension 28 of the plate 1 in front of the tongue 2, said extension being separated from the main portion of the plate 1 by a transverse slot or opening 11 extending between the bent side edges 7 of the plate. The portion of the belt to be connected with the tongues 2, 6 is inserted through the slot 11 from the rear side of the buckle, and thereafter a stretching of the belt is effected by a pull in the portion 9' of the belt. Thereafter the belt is connected with the tongues 2, 6 in the manner described above and as indicated by dot-and-dash lines 9''.

The stretching member is used when a tight stretching of the belt is required and the rear side of the buckle does not receive sufficient support by the object round which the belt is fastened. Without the stretching member one incurs the risk, when the buckle is made of relatively weak material, that the buckle will be folded inwards so that the resilient tongue 2 is disengaged from the belt.

In the embodiment of Figs. 8-12 the buckle proper has the same design as in Figs. 1-3. The buckle is intended to be attached to a portfolio and to co-operate with the strap of the cover of said portfolio so as to hold this cover in closed position. This connection of the buckle is effected in the same manner as described with reference to Figs. 4 and 5. Figs. 8-12 are intended to illustrate a device for securing the buckle in locking position. This securing device comprises a flat sleeve or socket 12 which embraces and is slidable along the strap. The rear side of this sleeve is provided with a recess 13, 14 having a round portion 13 connected with a portion 14 widening towards and open at the upper edge of the sleeve. When the strap 3 is clasped to the buckle and the tongues project into the holes 10 of the strap, the sleeve 12 may be moved, for example, from the position shown by dot-and-dash lines 15 in Fig. 11 to the position shown by full lines in the same figure. In this movement the extreme end of the tongue 2 is guided through the tapering portion 14 of the recess 13, 14 into the round portion 13 of the same recess and, due to its resilient character, it projects into and engages with the latter. The point of the tongue in this position is covered by the sleeve and cannot be contacted. The strap is released from the buckle simply by a pull downwards in the strap so that the tongue 6 is released, whereupon the sleeve 12 can slide down to its first position.

In the embodiment of Figs. 13-16 the plate 16 has no bent edge portions and has an extension 17 which together with the plate 16 forms a spring clip. The extreme end 61 of the plate 16 is bent and forms a resilient tongue, and the other shank 17 of the clip is of less length than the shank 16 and has the extreme end portion 18 bent toward the shank 16. The resilient tongue 29 is formed by a member which is riveted or attached in any other suitable way to the inside of the shank 16 and projects at its free end through a hole 19 in the shank 16. The outer edge of the tongue 29 and the outer edge of the tongue 61 are concave as shown at 29 and 21, respectively, but in certain cases it may be suitable that one or both of these edges be made convex. As shown by Fig. 16, this buckle is designed to be used as holder for a pen 22, in which case the clip 16, 17 embraces the edge portion 23 of the pocket of a coat or waist-coat. The bent end portion 18 of the shank 17 may be provided with one or more teeth and the shank 17 may also be provided with transverse grooves as shown in order to secure the device to the edge of the pocket. In order to connect a pen or pencil with this holder the pen or pencil is provided with two annular collars 25 at a suitable distance from each other, and the tongues 29 and 61 may be forced beneath these collars, so that the pen thereby is connected to the holder. As shown by Fig. 17 the pen 28, in lieu of the collars, may be provided with annular grooves 26 adapted to engage with the resilient tongues 29, 61 so that the pen is secured to the

holder. When the pen is to be moved from the holder it is only necessary to force the pen downwards so that it is disengaged from the tongue 61 and to swing the pen a slight angle from the holder whereupon the pen can be taken out of the pocket.

With advantage a buckle of this kind may also be used for the connection of a watch, a locket or the like to a pocket.

In the buckle of Figs. 18-20, the plate 31 with the short tongue 6 and the bent edges 71 is formed of sheet metal, as is the case with the embodiments described above, but the resilient tongue 27 is formed by a steel or other metal wire. This has the form of a fork having the end portions of its shanks inserted into and attached to the bent edge portions 71 which extend only along a portion of the longitudinal edges of the plate. The outer or bottom portion 20 of the fork 27 is considerably narrower than the width of the plate 31 and is bent out from the plate. As may be easily understood the manner of operation of this embodiment of the invention is substantially the same as that one described with reference to Figures 4 and 5.

The invention is not restricted to the embodiments above described with reference to the drawings but the details thereof may be varied within the scope of the appended claims.

What I claim is:

1. A buckle comprising in combination a substantially rigid plate having an outer and an inner substantially flat face and provided with a U-shaped cut-out forming a U-shaped plate portion; said U-shaped plate portion being bent out of the plane of said plate in inward direction so as to form a relatively long resilient tongue pointing in a predetermined direction; securing means on said outer flat face of said plate for securing the same to a support with said outer face superimposed upon said support; another tongue on said plate arranged spaced from said relatively long resilient tongue and being substantially shorter than the same, said other tongue projecting inwardly beyond said inner face of said plate and pointing in the opposite direction from the direction into which said relatively long resilient tongue points.

2. A buckle comprising in combination a buckle member composed of a substantially rigid plate having an outer and an inner substantially flat face and two flanges along opposite edges of said rigid plate projecting inwardly beyond said inner flat face of said buckle member; securing means on said outer flat face of said plate for securing the same to a support with said outer face superimposed upon said support; a first substantially rigid tongue on said plate projecting inwardly from the inner face of said plate; and a second substantially resilient tongue on said plate projecting also inwardly from said inner face thereof and being substantially longer than said first substantially rigid tongue, said two tongues being arranged spaced from each other and pointing outwardly in opposite directions from each other.

3. A buckle comprising in combination a buckle member composed of a substantially rigid plate having an outer and an inner substantially flat face and two flanges along opposite edges of said rigid plate projecting inwardly beyond said inner flat face of said buckle member, said substantially rigid plate being provided with a U-shaped cut-out forming a U-shaped plate portion; said U-shaped plate portion being bent out of the

plane of said plate in inward direction so as to form a relatively long resilient tongue pointing in a predetermined direction; securing means on said outer flat face of said plate for securing the same to a support with said outer face superimposed upon said support; another tongue on said plate along one of the free edges of the same arranged spaced from said relatively long resilient tongue and being substantially shorter than the same, said other tongue projecting inwardly beyond said inner face of said plate and pointing in the opposite direction from the direction into which said relatively long resilient tongue points.

4. Connecting arrangements for connecting two parts to each other comprising in combination a band-shaped member on one of said parts provided with at least two holes arranged at a predetermined distance from each other; a buckle member composed of a plate having two opposite parallel edges arranged at a distance from each other which is slightly greater than the width of said band-shaped member and having an outer and an inner substantially flat face, and two flanges along said opposite parallel edges of said plate projecting parallel to each other beyond said inner flat face of said buckle member; securing means on said outer flat face of said plate forming part of said buckle member for securing said buckle member to the other of said parts with said outer face of said plate superimposed upon said other part; a first substantially rigid tongue on said plate projecting inwardly from the inner face of the same and extending in a direction substantially parallel to said opposite parallel edges of said plate; and a second substantially resilient tongue on said plate projecting also inwardly from said inner face thereof, being substantially larger than said first tongue and pointing in opposite direction from the direction into which said first tongue projects but also substantially parallel to said opposite edges of said plate, said two tongues being arranged spaced from each other at such a distance that the distance between their points is slightly smaller than the distance between said holes in said band-shaped member.

5. Connecting arrangements for connecting two parts to each other comprising in combination a band-shaped member on one of said parts

provided with at least two holes arranged equidistant from the longitudinal edges of said band-shaped member and at a predetermined distance from each other; a buckle member composed of 5 a substantially rigid longitudinal plate having two opposite edges arranged at a distance from each other which is slightly greater than the width of said band-shaped member and having an outer and an inner substantially flat face, and 10 two flanges along said opposite parallel edges of said longitudinal plate projecting parallel to each other beyond said inner flat face of said buckle member; securing means on said outer flat face of said longitudinal plate forming part of said buckle member for securing said buckle member to the other of said parts of said outer face of said longitudinal plate superimposed upon said other part; a first relatively short tongue on said longitudinal plate arranged equidistant from said 15 opposite edges thereof projecting inwardly from said inner face of the same and extending in longitudinal direction of said longitudinal plate; and a second relatively long tongue on said longitudinal plate projecting also inwardly from said 20 inner face thereof extending also in longitudinal direction of said longitudinal plate, but pointing in opposite direction from the direction into which said first tongue projects, said two tongues being arranged spaced from each other at such 25 a distance that the distance between their points is slightly smaller than the distance between said holes in said band-shaped member.
